UNITED STATES PATENT OFFICE.

JAMES P. BURKE, OF NEWARK, NEW JERSEY.

DESIGN FOR AN INSTRUMENT KNOB OR SIMILAR ARTICLE.

Application filed March 31, 1925. Serial No. 12,965. Term of patent 7 years.

To all whom it may concern:

Be it known that I, JAMES P. BURKE, a citizen of the United States, residing in Newark, in the county of Essex and State of New Jersey, have invented a certain new, original, and ornamental Design for Instrument Knobs or Similar Articles, of which the following is a specification, reference being had to the accompanying drawings, forming a part thereof, and of which—

Figure 1 is a face view, and Fig. 2 is a side elevation of an instrument knob or similar article showing my new design.

I claim:

The ornamental design for an instrument knob or similar article as shown.

JAMES P. BURKE.
